LOCOMOTIVE DRIVING BOX LUBRICATOR

George H. Zouck, Orange, N. J., assignor to
Franklin Railway Supply Company, New York,
N. Y., a corporation of Delaware

Application January 18, 1927. Serial No. 161,738

8 Claims. (Cl. 308—83)

This invention relates to lubricators, particularly to lubricators adapted to use a cake of grease of a width substantially less than the distance between the box legs.

Such lubricators are more efficient in the use of grease than the type which accommodates a cake of substantially the same width as the distance between the box legs, as the lubricating qualities of the larger cake with its extended area contacting with the journal deteriorate to an extent which impairs the lubrication of the journal considerably before the cake is entirely used. Hence, in order to maintain proper lubrication of the journal at all times, the larger cakes have to be renewed before they are entirely used up. The smaller cake, presenting a smaller area to the journal is fed up to the journal more rapidly and is entirely used up before its lubricating qualities materially deteriorate and, consequently, waste is eliminated.

The primary object of the present invention is to provide means, which will be automatically advanced as wear occurs in the bearing brass, for effectively protecting those portions of the journal surface which lie between the sides of the grease cake and the box legs.

More specifically, I provide journal protecting flanges carried by the side walls of the lubricant container or cellar and means for supporting and advancing said cellar with its flanges independently of the action of the grease and its supporting means.

How the foregoing together with other objects and advantages are obtained will be clear from the following description of the preferred embodiment of the invention considered in connection with the accompanying drawing, wherein

Fig. 1 is a front view, half in elevation and half in section, of a locomotive driving box lubricator embodying my improvements, the section being taken on the line 1—1 of Fig. 2.

Fig. 2 is a view partly in side elevation and partly in longitudinal section, the section being taken on the line 2—2 of Fig. 1.

Fig. 3 is a section on an enlarged scale taken on the line 3—3 of Fig. 1, illustrating a detail of my invention.

Referring now to the drawing, the reference character 3 indicates a locomotive driving axle journal and 4—4 indicate the legs of the driving box. A spreader member, indicated as a whole, by the reference numeral 5, is positioned between the legs 4—4 of the box and comprises a rear wall

6, side walls 7, and lugs 8 which extend laterally from each corner of the spreader and abut

against the box legs 4—4. These lugs are originally made long enough to fit any size of box in common use and may be machined down to fit the smaller sizes. The side walls 7 are provided with webs 9 for strengthening the rear wall. Apertured lugs 10 are also provided on the side walls to receive the pin 11 for securing the cover plate 12 in closed position.

The walls 7 provide a guiding pocket for the grease cellar 13. The cellar comprises a rear wall 14 and side walls 15 which carry the protecting flanges 16. At each end of each flange I provide strengthening ribs 16a, the inwardly extending portions 16a, of which, contact with the journal, thereby protecting the portions of the journal bearing surface which lie between the cellar walls 15 and the box legs 4—4.

The cellar 13 also carries lugs 17 extending outwardly over the side walls of the spreader member. Leaf springs 18 are secured to the lugs 17 and bear against the top edges of the walls 7, thereby keeping the flanges 16 adjacent the journal bearing surface at all times.

A grease cake 19 is supported in the cellar on a follower plate 20, which, in turn, is supported by the springs 21, extending downwardly through openings 22 in the bottom of the cellar and seating on the spreader member 5. A perforated plate 23 is interposed between the upper surface of the grease cake and the journal.

Links 24 are provided on the follower plate for inspecting the lubricator and also for relieving the follower tension when inserting a new cake of grease.

According to the foregoing I provide a lubricator which is adapted to use a relatively small cake of grease and which, at the same time, affords effective protection for those portions of the journal bearing surface which lie between the cake and the box legs. Furthermore, the protecting flanges and the grease cake are provided with independent supporting means, so that the operation of one does not depend on the operation of the other.

I claim:

1. In a driving box lubricator, the combination of a spreader, a cellar, means reacting against the spreader for urging the cellar toward the journal, a grease cake in the cellar, an aperture in the cellar bottom, and means extending through said aperture and reacting against the spreader for urging the grease cake toward the journal.

2. In a driving box lubricator, a spreader, a cellar of a width substantially less than the dis-

100

105

110

tance between the box legs, said cellar having outwardly projecting flanges adapted to protect the journal, and means reacting between the spreader and the cellar for urging the cellar toward the journal.

- 5 3. In a journal lubricator, the combination of a spreader, a cellar, a grease cake in said cellar, means for urging said cake upwardly against said journal, flanges on said cellar for protecting 10 a portion of the journal bearing surface on each side of said cake and means for urging said cellar with its flanges upwardly against the journal independently of said first mentioned means.
- 15 4. A journal lubricator comprising in combination with the box legs, a spreader member between said legs having side walls spaced inwardly from its edges, a cellar member, journal protecting flanges carried by said cellar and extending 20 therefrom around the journal toward the box legs, together with means comprising springs and lugs secured to said cellar, for urging said cellar member upwardly.
- 25 5. In combination with a railway vehicle axle box, lubricating equipment for the axle journal including a grease cake of width substantially less than the distance between the legs of the box, spring means for urging said cake against the journal, a device having plate or flange like parts 30 adapted to protect portions of the journal bearing surface between said cake and the box legs, and additional spring means substantially independent of the spring means first mentioned for urging said device upwardly against the journal, 35 whereby said cake and said device are independently supported and lubrication of the journal bearing surface will continue even upon breakage or failure of the spring means for supporting said device.
- 40 6. In combination, a railway vehicle axle journal, a box structure surrounding the journal and having legs extended downwardly at opposite sides thereof to define the side walls of a lubricator cavity, a normally fixed base between said 45 legs for supporting lubricator elements in said cavity, a grease cake in said cavity of width substantially less than the distance between said legs, spring means reacting between said base and said cake for yieldingly urging the latter upwardly against the journal, a device having plate or 50 flange like parts adapted to protect portions of

the journal bearing surface between said cake and the legs of the box structure, and separate spring means reacting between said base and said device for yieldingly urging the latter upwardly toward the journal, the two spring means being operatively independent so as to ensure continuance of lubrication even upon breakage or failure of the spring means for supporting the said device.

- 55 7. In combination with a railway vehicle axle journal, a box structure surrounding the journal and providing a lubricator cavity therebelow with generally upright side walls, said box structure further including a base part defining the bottom wall of a lubricator cavity, a pair of guide flanges projecting upwardly from said base, said flanges being extended axially of the journal and being spaced from the side walls of the cavity, a grease cake between and laterally positioned by said flanges, said grease cake being removable from and replaceable in the box structure endwise between its guide flanges, curved plate-like elements for protecting the journal bearing surface between said cake and the side walls of the lubricator cavity, spring means for urging said plate-like elements upwardly against the journal, and separate spring means for urging said cake upwardly against the journal, the two spring means being operatively independent so as to provide for continuance of lubrication even upon breakage or failure of the spring means for supporting the journal protecting plates.

8. In a locomotive driving box lubricator, the combination of a box structure surrounding the driving axle journal and having side legs extended downwardly to define the lateral walls of a lubricator cavity, a spreader member between the box legs forming the bottom wall of said cavity, a lubricant cellar in said cavity of width substantially less than the distance between the 115 box legs, the cellar being mounted for movement toward and away from the journal, flanges carried by said cellar and extended laterally and upwardly from its side walls, and means reacting between the spreader member and the cellar for 120 urging the cellar upwardly toward the journal, whereby the flanges serve to protect journal bearing surface areas between the box legs and the cellar at each side of the latter.
